UNITED STATES PATENT OFFICE.

FRANK E. THOMPSON, OF PIERSON STATION, ILLINOIS.

SNOWPLOW.

Application filed November 16, 1925. Serial No. 69,454.

This invention relates to means for clearing pavements, highways and roads generally of snow and provides a plow which may be readily applied to or removed from a 5 tractor, and which may be adjusted at the front to admit of the propelling force being applied to hold the nose of the plow upon the road with a greater or less pressure as required.

10 The invention furthermore provides a plow which may be cheaply constructed, maintained at a little or no expense and which is effective, durable and easily manipulated.

15 While the drawings illustrate a preferred embodiment of the invention it is to be understood that in adapting the means to meet specific needs and requirements the design may be varied, and such other changes in 20 the minor details of construction may be resorted to within the scope of the invention as claimed, without departing from the spirit thereof.

For a full understanding of the invention 25 and the merits thereof, reference is to be had to the following description and the drawings hereto attached, in which,—

Figure 1 is a top plan view of a snow plow embodying the invention, showing the 30 same applied to a conventional tractor.

Figure 2 is a vertical, central, longitudinal sectional view of the plow.

Figure 3 is a vertical, transverse sectional view on the line 3—3 of Figure 2, looking 35 in the direction of the arrows, and

Figure 4 is a detail perspective view of the nose of the plow.

Corresponding and like parts are referred 40 to in the following description and designated in the several views of the drawings by like reference characters.

The numeral 1 designates a tractor of any 45 approved type the same being illustrated to demonstrate the application of the invention.

The plow comprises clearer blades 2, which are oppositely inclined and of a length to extend along opposite sides of the tractor, as illustrated most clearly in Figure 1. The blades 2 may consist of planks 50 and are reinforced at their lower edges by angle bars 3 which sustain the wear and strengthen the blades. Couplings 4 and 5 are applied to the nose of the plow and 55 connect the forward ends of the blade 2, the coupling 4 being disposed against the

forward side of the nose and engaging the outer faces of the blades 2 adjacent the point, whereas the coupling 5 is arranged upon the rear side of the nose and in contact with the rear faces of the blades 2 adjacent the point, the two couplings 4 and 5 being riveted or otherwise secured by suitable fastening means. The lower forward portion of the nose is beveled, as indicated 60 at 6, to ride over obstructions as will be readily appreciated. The forward ends of the reinforcing bars 3 underlap the lower ends of the wings comprising the forward coupling 4. The lower, rear corners of the 70 blades 2 are beveled, as indicated at 7, to insure riding over obstructions when the plow is backed.

A cross bar 8 extends between the forward ends of the blades 2 and receives a clevis 9 which is attached to the rear side thereof, and which comprises a vertical rib in which is formed a vertical series of openings 10 which provide for vertical adjustment of a push bar 11 which is attached at its rear 80 end to the front of the tractor 1. In this manner the pushing force may be adjusted vertically with a greater or less pressure as required. Vertical strips 12 are attached to the inner faces of the blades 2 adjacent the 85 nose and support the cross bar 8 and sustain the forward pressure exerted thereon. Stay chains 13 connect the rear end of the push bar 11 with the blades 2 and serve to prevent lateral displacement of the plow and 90 cause the same to run in a straight line.

A rear cross bar 14 is connected centrally to the rear of the tractor 1 and projects beyond opposite sides thereof and the projecting ends are bracingly connected to the 95 respective blades 2 by means of bars 15 and 16, the bars 15 being longitudinally disposed whereas the bars 16 are oppositely inclined. These bars 15 and 16 may be connected to the respective parts in any preferred way 100 and when the bars consist of wood they are reinforced at their ends by metal straps 17 which are connected to brackets 18 applied to the parts to which the stay bars 15 and 16 are connected. It is also observed that 105 similar brackets 18 are attached to the blades 2 for reception of the outer ends of the chains 13. Strips 19 are attached to the inner faces of the blades 2 and extend vertically and serve to strengthen the blade and 110 also to receive the brackets 18 which are connected thereto.

The snow plow will be of such dimensions as to receive the tractor between the blade 2, longitudinal stay bars 15 and 16 and the rear cross bar 14, as shown most clearly in Figure 1. In the operation of the device the plow is advanced by a pushing force applied thereto through the bars 11, 15 and 16, lateral displacement of the plow being prevented by the parts 13, and 14, as will be readily appreciated. This construction is such as to admit of the plow being readily placed in position for use and easily and quickly removed to be stowed away when not required for immediate service.

Having thus described the invention, I claim:

The combination with a tractor, of clearer blades at the sides thereof and forwardly

converged, a cross bar connecting the clearer blades adjacent their forward ends, a clevis attached to the cross bar and having a vertical rib in which a vertical series of openings is formed, a push bar adjustably connecting the front end of the tractor with the rib of said clevis, flexible elements adjustably connecting the rear end of the push bar with the clearer blades, a cross bar connected to the rear end of the tractor, longitudinal stay bars at the sides of the tractor connecting the outer ends of the rear cross bar with intermediate portions of the said blades, and forwardly diverged stay bars connecting the ends of the rear cross bar with the rear ends of the said blades.

In testimony whereof I affix my signature.
FRANK E. THOMPSON. [L. s.]
